UNITED STATES PATENT OFFICE.

NESTOR MAMBOURG, OF LANCASTER, OHIO, ASSIGNOR TO THE LIBBEY-OWENS SHEET GLASS COMPANY, OF TOLEDO, OHIO, A CORPORATION OF OHIO.

SECTIONAL LIP TILE.

Application filed March 19, 1925. Serial No. 16,654.

The present invention relates to sheet glass apparatus, and has particular reference to a new type of lip-tile for use in connection therewith.

5 An important object of the invention is to provide a lip-tile for use in connection with sheet glass apparatus, the said lip-tile being so constructed that a portion thereof can be replaced without interfering with 10 the normal operation of the said machine.

Another object of the invention is to provide a lip-tile of this nature comprising a plurality of parts whereby the main part or body portion of the lip-tile can be mounted 15 in position, other parts of the tile being so associated with the body portion that they can easily be removed and replaced without interference to the drawing of a sheet.

Other objects and advantages of the invention will become apparent during the course of the following description.

In the drawings wherein like numerals are employed to designate like parts throughout the same—

25 Fig. 1 is a fragmentary vertical longitudinal section through a portion of a sheet drawing apparatus illustrating my invention in use,

Fig. 2 is a transverse vertical section 30 thereof,

Fig. 3 is a fragmentary sectional view of a slightly modified form, and

Fig. 4 is a sectional view of still another form.

35 The invention is herein illustrated as used in conjunction with the machine disclosed in the Colburn Patent No. 1,248,809, granted December 4, 1917, wherein a sheet 5 is drawn from a source of glass 6 disposed in a draw-

40 pot 7, and being in open communication with a tank furnace 8, by which means the sheet source or meniscus 9 is continuously replenished. Sheet edge engaging rolls 10 are provided to build up an edge and to retard the movement thereof sufficiently to create an

45 edge on the sheet capable of maintaining the same to width after it has been formed. The sheet is bent over a so-called bending roll 11 whereby the sheet may be run in a horizontal plane over an idler roll 12, draw table 13, and through an annealing leir which is not shown.

50 The Colburn patent also disclosed the use of cover-tiles or so-called lip-tiles to protect the sheet 5 in its vertical run from heat cur-

rents and radiated heat which otherwise would strike the sheet. The heat currents or rays come from the tank furnace 8 on one side of the sheet and from below the pot 7 in the chamber 14. The entire pot is heated 60 by means of burners disposed in the chamber 14. In the Colburn patent the lip-tiles are arranged approximately as shown in Fig. 1, but in the Colburn patent and in all of the machines used under the Colburn patent, 65 each lip-tile has been constructed as a single unit. The lip-tiles are supported from above by means of a pipe or cable extending through a suitable aperture formed in a portion thereof. They are usually formed from 70 a refractory clay material and are of a length substantially the same as the width of the pot which varies from three feet upward. Due to the extreme length and huge- 75 ness of the lip-tiles necessitated to give strength thereto, considerable difficulties have been encountered due to cracking and breakage of the lip-tiles with result that pieces of the clay have dropped into the pot and caused considerable damage. Furthermore, the heat present around the draw-pot 7 makes it an exceptionally tedious job to remove and replace the lip-tiles without stopping the drawing of the sheet 5.

80 In the present invention it has been the aim to design a lip-tile which may be rigidly supported in position above the source of glass 6 and which is formed in sections so that the lip which is the part that usually cracks or breaks may easily be removed and 85 replaced.

In Fig. 1 the lip-tiles are shown as comprising a body portion 15 and what may be termed a lip-portion 16. The body portion is provided with a longitudinally extending opening 17 through which a suitable support 18 in the nature of an internally cooled pipe may be run. Suitable strap members 19 engage the pipe 18, and are carried by the member 20.

100 As is shown, the body portion 15 is provided with a longitudinally extending groove 21 adapted to receive a tongue 22 of the lip 16. The curvature of the tongue 22 approximates the curvature of the groove 21. An abutment 23 engages another portion of the lip 16 to hold the lip rigidly in position.

105 The lip 16 may be provided with a plurality of apertures 24 in which may be inserted prongs 25 carried by a grapple 26

- indicated in dotted lines. The grapple 26 may be raised, thus disengaging the lip 16 from the body portion 15. In this manner the lip may very easily be replaced when desired. The lip portion 16 may be formed in either three or four sections so that they may be slipped onto the body portions and slipped off with ease. In this instance the grapple 26 may be disposed with.
- 10 Figs. 3 and 4 show a slightly modified construction, but it will be seen that the lip portion 27 has engagement with the body portion 28 similar to the type of tiles shown in Fig. 1.
- 15 Although the lip tiles have been modified to facilitate removal of the lip portions, it is to be understood that they can be arched to function exactly as the present type of tiles in machines constructed in accordance 20 with the Colburn process. It is seldom that the cracks or breaks begin in the body portions of the tiles, but as a rule the crack or other fracture begins in the lip portion and extends through the body. This fact is 25 taken advantage of in the present invention by separating the lip and the body and making it possible to easily and quickly replace a lip with a minimum of expense and time.
- 30 It is to be understood that the form of the invention herewith shown and described is to be taken as the preferred embodiment of the same, and that various changes in the shape, size and arrangement of parts 35 may be resorted to without departing from the spirit of the invention or the scope of the subjoined claims.

Claims:

1. In sheet glass apparatus, means for 40 drawing a sheet from a mass of molten

glass, and a lip-tile arranged above the molten glass and comprising a body portion and a removable lip portion.

2. In combination with a sheet drawing apparatus, of a lip-tile comprising a body 45 portion and a lip portion removably associated therewith.

3. In combination with a sheet drawing apparatus, of a lip-tile comprising a body portion and a lip portion for removable engagement.

4. In combination with a sheet drawing apparatus, of a lip-tile comprising a body portion having a groove therein and a lip portion having means adapted to be received within said groove.

5. In combination with a sheet drawing apparatus, of a sectional lip-tile comprising a body portion and a lip portion, the body portion having a groove therein and the lip portion carrying a tongue adapted to be received in the said groove whereby the lip may be supported in operative position.

6. In combination with a sheet drawing 65 apparatus, of a lip-tile comprising a stationary body portion and a removable lip portion.

7. In combination with a sheet drawing apparatus, of a lip-tile comprising a stationary 70 body portion and a removable lip portion, the body having a groove therein and the lip carrying a tongue adapted to be received in the said groove, and an abutment carried by the body and engaging the 75 lip.

Signed at Lancaster, in the county of Fairfield, and State of Ohio, this 16th day of March, 1925.

NESTOR MAMBOURG.
